UNITED STATES PATENT OFFICE.

WILLIAM WALKER, OF LANGSIDE, GLASGOW, SCOTLAND, ASSIGNOR TO JOHN MACDONALD & SON LIMITED, OF MARYHILL, GLASGOW, SCOTLAND.

SUPPORT FOR PNEUMATIC TOOLS.

1,335,807.

Specification of Letters Patent.

Patented Apr. 6, 1920.

Application filed April 11, 1919. Serial No. 289,342.

To all whom it may concern:

Be it known that I, WILLIAM WALKER, of 17 Millbrae Crescent, Langside, Glasgow, Scotland, a subject of the King of Great Britain, have invented a certain new and useful Support for Pneumatic Tools, of which the following is a specification.

This invention relates to what is known as a "rig-up" for supporting pneumatic tools in shipbuilding and like work.

The object of the invention is to provide an improved construction of "rig-up" adapted particularly, for supporting pneumatic riveting hammers.

In order that the invention may be clearly understood I have hereunto appended an explanatory sheet of drawings showing the improved "rig-up."

Figure 1 is a plan view and Fig. 2 a side view of the device.

Fig. 3 is a cross section on the line 3—3, Fig. 1.

Fig. 4 is a cross section on the line 4—4, Fig. 1.

Fig. 5 is a side view of the device in position for work.

The device comprises a frame consisting of two parallel tubular members 1, 2, of about seven feet in length these members carrying, at the one end, a jaw or holder 3 for supporting the pneumatic hammer or other pneumatic tool this jaw being pivotally mounted, at 4, in the cross bar 5 connecting the tubes at that end. At the opposite end the members are connected by a cross bar 6 forming the base of the frame. Located centrally between the tubes 1, 2, is a shorter, third, tube 7 having, at the ends, blocks 8, 9, the block 8 carrying two rollers 10 and two grooved wheels 11, the rollers bearing against the one side of the tubes 1, 2, and the wheels engaging the other side—see Fig. 3. Similarly the block 9 has grooved wheels 12 and rollers 13^a engaging the tubes 1, 2,—see Fig. 4. It will be noted the grooved wheels 11 are at the one side of the tubes 1, 2, while the grooved wheels 12 are at the opposite side of the tubes. The block 9 has two lateral lugs in which is slidably fitted a tubular "reaction" or fulcrum bar 13 having a series of holes 14 therein and a keeper pin 15 adapted to pass through the holes and also through corresponding holes in the bottom lug this keeper pin being held by a chain 16. The bar 13 can be ad-

justed relatively with the tubes 1, 2, and held in adjusted position by passing the keeper pin through the lug of the block 9 and through one of the holes 14 in the bar. At the end of the bar is a bracket 17 carrying wheels 18. Connected to the tube 7 is a block 19 through which passes a threaded rod 20 this rod having on it a nut with arm 21 between which nut and the block a spiral spring 22 is fitted. The screw rod 20, which passes freely through the block, has a nut 24 on its end.

The construction is such that when the device is secured to the structure being riveted, say, a ship, the pneumatic hammer can be held in place in the jaw 3 and pivotally turned to suit the work. The tube 7 constitutes a support and is held in position, at the ship's side, by means of the threaded rod 20 which is passed through a hole in the ship's plating A (Fig. 5) and secured at the inside thereof by means of a nut and at the outside by nut 24. The spring 22, when the tube is so secured, gives a cushioning action which tends to press the frame toward the plating A and hold the hammer up to its work. The device is retained in place, at a desired distance from the ship's side, by means of the fulcrum bar 13 with its rollers 18 which latter bear against the plating, the bar being adjusted as desired by means of the holes 14 and pin 15. The spring can be compressed more or less, as desired, by the nut 21.

As the riveting proceeds the frame, if arranged vertically as shown at Fig. 5, can be pulled upward or pushed downward as desired, the frictional grip of the wheels and rollers being sufficient to hold it in place on the support 7.

Having now fully described my invention what I claim and desire to secure by Letters Patent is:—

1. A rig-up for supporting pneumatic riveting tools, comprising a frame composed of parallel members, a holder for the tool carried by the frame, a central support on which the frame is slidably arranged said support having end and intermediate blocks, guide wheels for the parallel members of the frame carried by the end blocks, means for securing the support, a cushioning spring in conjunction with the intermediate block, and a fulcrum bar carried by one of the end blocks, substantially as set forth.

2. A rig-up for supporting pneumatic riveting tools, comprising a frame composed of parallel members, a holder for the tool carried by the frame, a central support on which the frame is slidably arranged said support having end and intermediate blocks, a pair of guide wheels and a pair of rollers carried by each block and bearing on opposite sides of the parallel members of the frame, means for securing the support, a

cushioning spring in conjunction with the intermediate block, and a fulcrum bar adjustably carried by one of the end blocks, substantially as set forth.

In testimony whereof I affix my signature 15
in presence of two witnesses.

WILLIAM WALKER.
